UNITED STATES PATENT OFFICE.

EMILE RUELLE, OF BLANC MISSERON, FRANCE.

APPARATUS FOR DRYING PHOSPHATES.

SPECIFICATION forming part of Letters Patent No. 567,513, dated September 8, 1896.

Application filed January 3, 1894. Serial No. 495,552. (No model.) Patented in France January 28, 1887, No. 181,103, and January 14, 1893, No. 218,608, and in Belgium February 18, 1887, No. 76,391, July 11, 1890, No. 91,226, October 23, 1891, No. 96,924, December 6, 1892, No. 102,436, and July 22, 1893, No. 105,665.

To all whom it may concern:

Be it known that I, EMILE RUELLE, manufacturer, of Blanc Misseron, French Republic, have invented Apparatus for Drying Phosphates, &c., (for which I have obtained patents in Belgium, February 18, 1887, No. 76,391; July 11, 1890, No. 91,226; October 23, 1891, No. 96,924; December 6, 1892, No. 102,436, and July 22, 1893, No. 105,665, and in France, January 28, 1887, No. 181,103, and January 14, 1893, No. 218,608,) of which the following is a specification.

The present invention consists of an apparatus for the drying of phosphates or other mineral, animal, or vegetable matters after such materials have been washed.

In the accompanying drawings, Figures 1 and 2 are respectively an elevation and a plan of the apparatus for drying the washed products.

This drying apparatus consists of two truncated cones 25 and 26 of considerable length as compared to their diameter, being arranged concentrically one within the other with their 25 inclination reversed. At one end these cones are connected rigidly together and closed with the exception of a central opening communicating with the flue of a furnace 27. This is provided with opposite chambers, into 30 one of which air is forced by a fan, and which are connected by arched pipes, so that the air in passing through them to the opposite chamber becomes heated, being discharged thence into the inner conical drum. The internal surfaces of the drums have angle-iron ribs 28 of helical form. The end of the inner cone opposite that communicating with the furnace is provided with a charging-hopper 29, having a regulating device for controlling the entrance of the material. The outer cone has a ring 30, which can slide on the internal cone, so as to allow of independent expansion and contraction. In this ring are openings through which the dried material escapes. Near these discharge-openings, within the annular space between the two cones, are arranged crushing-balls 31, guided

by metal rings fixed to the internal cone, the before-mentioned helical ribs 28 being interrupted at these points. The outer cone has 50 a toothed ring 32 fixed on its outer surface, with which gears a driving-pinion through which the double cone receives a rotary motion. The outer cone also has circular rails 33, that run on stationary rollers carried in 55 bearings on the foundation. At 34 is provided a damper which serves to regulate the passage of the combustion-gases to a chimney. (Not shown in the drawings.) It also serves as a baffle-plate for retaining the light 60 particles that would be carried off by the draft, these particles being deposited at the bottom of the box, from which they are removed through side doors. If the combustion-gases are proved to be liable to injuriously affect the material to be dried, they 65 may be conducted away by a central flue passing right through the drums instead of entering directly into the latter. The materials are introduced through the hopper into 70 the inner cone, along which they travel in the contrary direction to the hot gases entering through the other end. In traveling along the materials are raised up by the helical angle-iron ribs 28 and allowed to fall again, 75 thus exposing them to a considerable extent to the action of the hot air. On arriving at the end of the inner cone they pass into the outer cone through openings 30, formed in the sides of the former, and then travel back 80 again in the latter, eventually escaping through the openings of the ring 30, whence they fall into a collecting-pit, from which they are removed by suitable means.

I claim as my invention—

In apparatus for treating phosphates and the like, a drying apparatus comprising two rotary concentric truncated cones having their inclinations reversed, crushing-balls between the two cones, angle-irons secured to 90 one of the cones to guide the said crushing-balls, the two cones communicating with each other at one end only, this end of the apparatus being provided with a furnace having

a flue opening into the inner cone, and means for forcing air into the inner cone, the other end of the inner cone being provided with a charging - hopper, and a chimney leading therefrom and having a damper, all substantially as set forth.

5 In testimony whereof I have signed my

name to this specification in the presence of two subscribing witnesses.

EMILE RUELLE.
